United States Patent Office

Des. 183,291

Patented July 29, 1958

183,291

BOAT DECK CLEAT

Clifford Brooks Stevens, Milwaukee, Wis., assignor to
The Vollrath Co., Sheboygan, Wis., a corporation of Wisconsin

Application December 12, 1957, Serial No. 48,876

Term of patent 7 years

(Cl. D71—1)

Fig. 1.

Fig. 2.

Fig. 3.

Fig. 4.

Fig. 1 is a perspective view of a boat deck cleat embodying my new design, showing the top, front, and one side thereof;

Fig. 2 is a top plan view thereof;

Fig. 3 is a front elevational view of the cleat; and

Fig. 4 is a side elevational view, the opposite side of the cleat being the same in appearance as the side shown.

I claim:

The ornamental design for a boat deck cleat, substantially as shown.
